UNITED STATES PATENT OFFICE.

GEORGE W. MAXWELL, OF LOS ANGELES, CALIFORNIA.

CABINET-DIRECTORY.

SPECIFICATION forming part of Letters Patent No. 697,377, dated April 8, 1902.

Application filed April 1, 1898. Renewed August 1, 1900. Serial No. 25,591. (No model.)

To all whom it may concern:

Be it known that I, GEORGE W. MAXWELL, a citizen of the United States, residing at Los Angeles, in the county of Los Angeles and 5 State of California, have invented new and useful Improvements in Cabinet-Directories, of which the following is a specification.

My directory employs in a practical manner one or more sets of rollers with long paper 10 strips rolled thereon and containing the printed names and addresses.

The objects of this invention are superior cheapness, convenience, durability, and easy reference; also, to provide a practical directory 15 which can be readily corrected and revised at frequent intervals; also, to provide a practical city or country directory of more convenient form and more durable than any book-directory in that the paper is protected 20 and not handled; also, to provide a practical directory which is better than the book-directory in that the names and addresses can be referred to in much less time.

The names in my directory for a city of, say, 25 one hundred thousand population, and which directory would ordinarily contain forty thousand names, if printed in nonpareil type, double column, would make a ribbon about one hundred and forty feet long. If divided into 30 only two sets—"A" to "L" and "M" to "Z"—instead of four, as herein shown, the ribbon for either set would be seventy feet long. The mechanism in my directory is so constructed and geared that by eight turns of a crank, and 35 which can be done in three seconds, every name in the directory from "A" to "Z" by operating both sets at once would be exposed to the eye of the operator. Much greater speed in rolling the paper ribbon or directory- 40 strip may be obtained, if desired, by increasing the diameter of the rollers and also by using gear in proper proportion to further increase the speed. It is practicable to do this owing to the lightness in weight of the paper 45 and the roller, and greatly increased speed can be obtained by a little additional effort on the part of the person turning the crank. Greater speed in rolling the paper might be desired only in case a longer ribbon were used.

50 My directory is designed to be more economical to publish in that the thinnest and cheap-

est quality of paper (even tissue-paper) can be used, whereas the same quality of paper (tissue or similar paper) would be unfit and impracticable for use in a book-directory. No 55 binding or cover is required with this directory excepting the permanent case which contains the mechanism. It is practicable to revise and correct the directory several times a year, even monthly, owing to the fact that 60 the lines of type can be kept standing in the forms, and the new lines of type containing changes of names and addresses and the new or additional names may be inserted at any time. As no binding is required and the very 65 cheapest and thinnest quality of paper can be used, several issues of my directory can be printed from these forms for a less cost than only one issue containing the same matter if printed and bound in the customary book 70 form. It is obvious that tissue or a light quality of paper if used in the ordinary bound book-directory would soon become ruffled, tangled, worn out, torn, and unreadable from the handling it would be subject to, while in 75 my directory the paper is protected by metal and glass and is never touched by the one using it. Thus it will be seen that my directory can be kept up to date, and the superiority of a number of revised and corrected 80 issues during a year containing removals, changes, and new information as compared with one issue of a customary yearly book-directory is plainly seen.

In this directory I have made provision for 85 the use of a plurality of sets of rollers and directory-strips, one for each set, and have made provision for the automatic operation of the particular set which is presented to view when the user turns the crank, and I provide 90 a plurality of the sides of the case with sight-openings, through which the directory-strips are exhibited.

For the purpose of illustration I have shown 95 in the accompanying drawings a directory contained in a case about seven inches square in cross-section, and there are sight-openings on the front and back sides of this case; but it is to be understood that I am not limited to any particular size or to the use of any particular number of sides, but may use one or 100 more sides, as may prove most convenient,

and the case could be made hexagon, octagon, or with any number of sides desired without departing from my invention.

The directory-case when provided on a plurality of sides with sight-openings is mounted to turn on journals having an axis preferably horizontal, and a plurality of sets of directory mechanisms are mounted in the case for exhibition through their respective sight-openings in the several sides. A crank-shaft extends through the case-journals and is journaled in the supports which carry the case-journals. Mechanism is provided for connecting the shaft with the directory mechanisms to drive them when the sight-opening for such directory-strip is in the position for reading and disengaging such shaft from the directory mechanisms that are not exposed, and means, such as a catch, are provided for temporarily connecting the case and the support to hold the case from turning. Preferably the catch holds the case in a fixed position, with the side of the case which is to be exhibited held in a slanting position, so as to be conveniently seen. A pair of rollers is provided for each sight-opening, and each pair has a directory-strip or ribbon for exhibition through such opening. Where a plurality of the sides of the case are provided with directory-strips, I provide means for automatically connecting the crank or driving shaft with the mechanism for driving the rollers to be operated, and at the same time disconnecting said shaft from the mechanism for driving the rollers which are not to be operated. In order to accomplish this, the shaft is eccentrically journaled in the case-journals and extending therethrough are journaled in the case-journal supports. A driving-wheel is provided on the shaft, and sets of roller-driving gearing, one set for each pair of rollers, are arranged symmetrically around the axis of the case-journals to respectively mesh with the driving-wheel when in a given position and to be withdrawn from the driving-wheel when out of such given position—that is to say, when the case is rotated upon its axis to bring the strip of one set of directory mechanism to view the gearing for driving that set of mechanism will be drawn into mesh with the driving-wheel and the gearing for the other set or sets of mechanism, if more than one set is employed, will be thrown out of gear with the shaft-gear. I also provide automatic means for positively driving that roller of any set toward which roller the crank is operated, and I also provide a shifting brake to apply friction to prevent the roller which is not being positively driven from racing when the other roller is operated, and the mechanism which I employ releases the operated roller at the same time that it brakes the other roller.

My invention includes the various features herein described and illustrated in the accompanying drawings.

In my pending application, Serial No.

737,688, filed November 20, 1899, for improvement in mechanical directories and the like and in my application for patent on indexed mechanical directory, (renewal,) filed August 7th 1, 1900, Serial No. 25,592, and my application for mechanical city-directory with automatic supplement and index, filed February 13, 1899, Serial No. 705,446, I have shown the combination with the rollers and the flexible strip fastened to said rollers to be wound and unwound from roller to roller; wheels for said rollers, respectively; wheels for driving the roller-wheels, respectively; a lever carrying said driving-wheels and pivoted to simultaneously hold one of the driving-wheels in operative engagement with its roller-wheel and the other driving-wheel out of engagement with its roller-wheel, and vice versa; a master-wheel journaled to revolve and operatively engaging with said driving-wheels and being frictionally connected with the lever to throw the lever in the direction of the rotation of the master-wheel, and means for rotating the master-wheel, and said combination is claimed in said application, Serial No. 737,688, filed November 20, 1899, and for this reason is not claimed in this application.

Figure 1 is a perspective view of one form of my newly-invented cabinet-directory in position for use. Fig. 2 is a sectional elevation on line 2 2, Figs. 3 and 4, looking to the left. Fig. 3 shows the case and mechanism as they would appear to the user if the door and directory-strips were removed. Fig. 4 is a section on line 4 4, Figs. 2 and 3, as it would appear to one standing in front of the machine and bending over and looking down and toward the front of the directory in a direction opposite to that in which he will look when using the directory. Fig. 5 is a fragmental detail to show the shifting mechanism for shifting the pinion from the one to the other axle of the axially-arranged rollers. Fig. 6 is a fragmental plan detail to illustrate the brake appliance. Fig. 7 is a detail elevation to further illustrate the brake appliance. Fig. 8 is a section of the brake appliance on line 8 8, Fig. 7. A portion of the roller is shown, but not in section. Fig. 9 is a sectional elevation of the mechanism for shifting the pinion from one to the other of the axially-arranged roller-shafts, taken on line 9 9, Fig. 10. Fig. 10 is an end view of one set of the directory-strip rollers, showing the pivoted lever carrying the pinions for transmitting power through the master-wheel from the operating-shaft to the strip-rolls and the pinion-shifting means.

A indicates the case of a directory which contains four sets 1 2 3 4 of directory mechanisms. These are arranged two sets 1 2 at the front and two sets 3 4 at the back of the case. All is incased in a metal box A, the sides of which are seven inches square. A door a, having glazed sight-openings a' in it, through which the names and addresses may be seen, is provided in front, and a like door

is provided in the back. The front and back of the case are duplicates, with the exception that they are marked to indicate that their directory-strips respectively refer to different portions of the alphabet. The names at the front may run from "A" to "L," while those at the back may run from "M" to "Z," or any other desired arrangement may be employed. The directory-case when being operated will stand with one side at an angle, preferably, of about forty-five degrees to make it easy to read the exposed portions of the directory-strips B B', &c.

C indicates a catch in one of the standards or supports D, which catches in a hole c in the case to hold the case at the desired angle. When the operator desires to turn the case to view the list at the other side, he will draw the catch and will then turn the case on its axis to bring the other set of rollers to the front.

c' indicates a spring to return the catch into its operative position to hold the case when it has reached the desired angle to expose the strips on the other side.

The case is provided with two journals a² a³, which are journaled in the supports D D', respectively, and the common axis of these journals passes centrally between the several sets of directory mechanisms.

E indicates the operating-shaft, provided at one end with a crank e and at the middle with a gear or driving wheel e'. The shaft E extends through the journals a² a³ and is journaled in the supports D D', eccentric the boxes d d' of the case-journals a² a³. The axis of the shaft E and the axis of the case-journals a² a³ and their boxes d d' are eccentric about one-eighth of an inch, the axis of the shaft being about one-eighth of an inch higher and about one-eighth of an inch farther toward the front than the axis of the case-journals and their boxes, so that when the case is rotated on its journals that side which is toward the front will be brought nearer the shaft and the driving-wheel thereon will be thrown into engagement with the master-wheel of the directory mechanism on that side and the side of the case which is to the back will be thrown farther away from the shaft and the master-wheels of the directory-strips on that side will be out of engagement with the driving-wheel on the shaft.

F F' indicate master-wheels mounted upon the shafts f f', respectively, which are carried by the cross-bars which support and carry the directory-strip rollers.

G indicates a lever journaled on the shaft f and provided at its opposite ends with pinions g g', which respectively mesh with the master-wheel F and are apart from each other somewhat less than one hundred and eighty degrees. One face of the master-wheel forms a frictional disk f², which is engaged by a friction-spring g'', fixed to the lever G and pressing against the frictional disk f² of the

master-wheel F, so that the rotation of the master-wheel F in either direction will cause the lever to swing in that direction, thus swinging the transmitting-pinions g g' one 70 into and the other out of mesh with their respective roller-pinions H H', which are respectively mounted upon the shafts i i', &c., of the rollers I I', &c.

By referring to Fig. 2 it will be seen that 75 when the set 2 of the directory mechanisms is at the front the master-wheel F will be in gear with the driving-wheel e', while the master-wheel F' will be out of gear with said driving-wheel, and that if the shaft is turned 80 to the right, thus turning the master-wheel F to the left, the friction of such wheel upon the friction-spring g'' will operate to throw the pinion-carrying lever G to bring the transmitting-pinion g' into engagement with the 85 roller-pinion H' to drive the roller I''' to rotate the same to wind the ribbon thereon, and at the same time the transmitting-pinion g is thrown out of gear away from the roller-pinion H of the roller I'', thus leaving the 90 roller I'' free to rotate, and that when this had been done a reverse movement of the crank would withdraw the transmitting-pinion g' from the roller-pinion H' and return the transmitting-pinion g to mesh with the roller- 95 pinion H, thus to rotate the roller I'' to wind the ribbon thereon and leaving the roller I''' free to allow the ribbon to unwind therefrom. In order to prevent racing of the released roller, I provide a shifting brake. 100

J indicates a rod, which is preferably square in cross-section.

J' indicates a tubular slide on the rod and carrying a brake-shoe J'', which engages the end or flange of either one of the rollers to 105 which it is applied by shifting along the rod. The rod is arranged to cause the shoe J'' to contact with the ends of the rollers, near the periphery thereof, so that when the one roller rotates to wind the ribbon upon such roller 110 the friction of such roller upon the shoe will cause the shoe to slide along the rod J toward the other roller and will throw it into contact with the end of the other roller, which is being rotated by the unwinding ribbon in the 115 same direction in which the shoe is moving, so that the shoe is by friction automatically shifted from the winding-roller to the unwinding-roller to release the one and to prevent the racing of the other. 120

K K' indicate springs to press upon the tube J' to hold the shoe firmly against the rollers. The tube plays loosely upon the rod, so that the springs can always force the shoe into operative contact with the roller to be 125 braked.

If desired, each sight-opening can be provided with two directory-strips, each carried by an independent pair of rollers, and the rollers of each pair may be arranged to be 130 connected and disconnected to operate simultaneously or separately at pleasure. The

roller-shafts i i'' are set coaxial with each other to form a unitary arbor for a shifting cog-wheel H , and the roller-shafts i i'' are coaxial with each other to form a unitary arbor for a shifting cog-wheel H' , and each shaft is provided with a projection, as the pin 1^1 2^1 , &c. The coaxial shafts end close to each other without touching, but together form the arbor for the roller cog-wheels H and H' , respectively, which are arranged to slide along their said respective arbors and are each provided with projections, as pins h h' , to respectively engage the pins 1^1 2^1 , &c., when the roller cog-wheels are fully shifted on their arbors for that purpose, to drive one or the other pair of rollers. When the cog-wheels are midway between the arbor-pins, the pins are not engaged.

L indicates a shifter carried by a shaft L' , which is journaled at l' to the case and is operated by a pointer-lever l'' , which extends to the front of the case to be moved to or from the indicated limit-letters "A to F" "G to L." The indicated letters on the other side 25 of the case for the pointer-lever on that side, which is not shown in the drawings, will be "M to Q" and "R to Z." These limit-letters respectively show the limits of the several ribbons or directory-strips.

30 It is to be understood that the alphabetical divisions of the lists may be varied as desired or as occasion demands.

In practical operation the user will first turn the case to expose the strip he desires 35 to inspect and will then set the pointer to the limit-letters which indicate the strip containing the name he wishes to find. He will then turn the crank in either direction until he brings to view that part of the strip where 40 the desired name should appear.

Now having described my invention, what I claim as new, and desire to secure by Letters Patent, is—

1. A directory or like information-exhibiting device comprising a revoluble case provided upon its different sides with sight-openings; mechanism for moving information-strip back and forth behind such sight-openings; means whereby one set of strip-operating mechanism is brought into operative connection with the central operating-shaft when the case is revolved to bring any one of the sight-openings into a predetermined position.

2. A directory or like information-giving device comprising the revoluble case provided upon several of its sides with sight-openings for displaying information printed upon strips; means for moving the strips back and forth behind the sight-openings; the case 60 mounted to revolve eccentrically whereby the central shaft engages with one of and disengages from the other strip-operating mechanisms.

3. A directory or like information-exhibiting device comprising a case provided upon its different sides with sight-openings; means

for passing such information back and forth behind such sight-openings; the operating-shaft; the driving-wheel mounted on such shaft; the master-wheels for operating the information-giving device; the eccentric bearings mounted in the revoluble case whereby an eccentric travel is imparted to the case to carry one set of strip-operating master-wheels out of engagement with the driving-wheel, 75 and another set into engagement therewith.

4. In a strip-directory, two sets of strip-operating rollers mounted coaxially; means for operating such rollers to wind the strip from one roller to the other roller in one of the sets of the strip-operating rollers; the pinion loosely mounted upon the ends of the coaxial roller-shafts; and means for shifting such pinion from one shaft to the other whereby one set of rollers is thrown into motion and the other set is left inoperative.

5. In a strip-directory, the two sets of strip-operating rolls mounted coaxial; a master-wheel; a pivoted lever carrying a pinion on each end; a friction device attached to the pivoted lever and bearing on the master-wheel; the pinion loosely mounted upon the coaxial roller-shafts and adapted to engage with the pinion on the pivoted lever when the lever is thrown in its direction; means for shifting the pinion from one roller-shaft to the other; and means for engaging the pinion with such shafts.

6. The combination of two rollers; a strip wound upon said rollers; means for alternately driving the one roller in one direction and at the same time releasing the other roller and for driving the other roller in the other direction and at the same time releasing the first roller; a rod extending parallel with the end faces of the rollers; a brake-shoe arranged to slide along the rod and to engage the end of one or the other of said rollers when shifted from one to the other of said rollers and adapted to be slid along said rod by the friction of one of said rollers to contact with and produce the friction upon the other of said rollers.

7. The combination of two pairs of rollers with directory-strips, one for each pair of rollers, the shafts of two of the rollers being set coaxial with each other to form a unitary arbor and the shafts of the other two rollers being set coaxial with each other to form a unitary arbor, and each roller-shaft being provided with a projection; two roller-driving cog-wheels, one mounted upon each of said arbors and each provided with lateral projections to engage the projections of the roller-shafts respectively when the roller-driving cog-wheel is shifted to one or the other of said roller-shaft projections; and means for shifting the roller-driving cog-wheels.

8. The combination of two directory-ribbon rollers; a cog-wheel fastened to one of said rollers; a cog-wheel fastened to the other roller; a driving-shaft; a master-wheel and frictional disk fixed on the driving-shaft; a

lever journaled coaxial with the master-wheel and provided at each end with a transmitting-pinion, said pinions meshing with and driven by said master-wheel to independently mesh with the cog-wheels of the respective rollers when the lever is vibrated in one or the other direction; and a frictional device fixed to the lever and engaging the frictional disk on the

master-wheel to cause the rotation of the master-wheel to shift the lever to mesh a transmitting-pinion with one or the other of the roller cog-wheels. 10
